R. W. STANLEY
EXTENSION PACKING CASE

Filed May 1, 1925

4 Inventor,
Robert W. Stanley,
By his Attorney.
Ramsay H. Agnew.

UNITED STATES PATENT OFFICE.

ROBERT W. STANLEY, OF HOLYOKE, MASSACHUSETTS, ASSIGNOR TO BERGSTAN PATENTS CORPORATION, OF WILMINGTON, DELAWARE, A CORPORATION OF DELAWARE.

EXTENSION PACKING CASE.

Application filed May 1, 1925. Serial No. 27,163.

My invention relates to improvements in knock-down metal packing cases, and this invention while not limited to use in connection with my prior application, is nevertheless well adapted for use in connection with a structure such as that shown in my application for Letters Patent of the United States Serial No. 727,477, filed July 22nd, 1924.

10 In packing cases such as disclosed in my prior application, I find that it is a very simple matter to extend such packing cases in any direction, preferably in depth, without changing the essential characteristics of 15 the packing case, that is to say, I can preserve the general shape, the inclined corners, the fastening flanges which lie within the planes of the adjacent sides and are arranged to strengthen the structure without 20 inconvenience, and in fact all the advantages specified in the specification of my prior application. Packing cases of this type are re-usable, and it sometimes happens that it is very desirable to make the packing case 25 larger because of some other use for it, and my invention is intended to meet this requirement and to provide a simple and inexpensive structure which will enable such extension to be readily made. This will be 30 better understood from the description which follows.

Reference is to be had to the accompanying drawings forming a part of this specification, in which similar reference characters indicate corresponding parts in all the 35 views.

Figure 1 is a side elevation of my improved packing case.

Figure 2 is a cross section thereof on the 40 line 2—2 of Figure 1.

Figure 3 is a side elevation of a slightly modified form of the invention, and

Figure 4 is a cross section on the line 4—4 of Figure 1.

45 The body of the packing case can be of any usual type having the sides and ends provided with outwardly extending flanges at top and bottom and at the vertical corners, but I have shown the invention in connection with a structure like that in my prior application referred to, because it is so easy 50 to apply it to this type. As illustrated the main or lower part of the case is practically like that shown in my prior application,

having opposed sides 10 with inclined parts 55 11 at top and bottom, and outwardly extending flanges 12 which correspond to flanges 13 on the bottom 14. The ends 15 are like those in my other application, and are similar to the sides just described. As illustrated in Figures 1 and 2 I use a type of extension comprising side and end portions 16 and 17 which can be corrugated like the other parts to give the necessary strength, and which can be united at the vertical corners by flanges 16^a or in any suitable way, and these side and end pieces have at the bottom upturned flanges 18 which are adapted to seat firmly on the flanges 12 of the lower case section, while the top edges of said 60 parts have outwardly and upwardly extending flanges 19 preferably parallel with the flanges 18 and adapted to receive the corresponding flanges 20 on the inclined part 21 of the cover 22.

75 It will be observed that if the extension 16—17 were not used, the cover 22 would fit on the lower part of the case precisely as shown in my former application, but by adding the extension, the cover applies to the 80 top of this part and the case is therefore considerably deeper. It will be seen that I preserve the characteristics of the original case, that is that the sides and ends may be corrugated for strength, may have the inclined 85 parts and the connecting flanges, and it will be noted that the flanges 18 and 19 lie within the plane of the wider part of the lower portion of the case so that no loss of space in shipping occurs. Also it will be seen by 90 reference to Figure 2 that I can preserve the arrangement referred to in my prior case of having the meeting flanges 12 and 13 spaced in such a way as to permit a hook to be easily placed under them. Furthermore 95 it will be noted that the extension 16—17 may be of any desired height, and that a plurality of extensions could be as easily used, and it will also be noticed that while I have shown an extension to the top, that as 100 the sides, ends, and bottoms of the main part of the casing all have the outwardly extending flanges, the extension 16—17 might as well be put on the sides or ends as on the top, but the latter would be the usual way of applying the extension. It will thus be seen that by having one or more extensions, the packing case may be very easily and eco- 105

nomically adapted to contain more or less material as desired.

In Figures 3 and 4 I have shown a slightly different type of extension in which the extension part is formed of the side pieces 22 and end pieces 23 precisely like those of the lower part of the case, and like the structure described in my prior application. As illustrated in these figures, the side pieces have inclined parts 24 and outwardly extending flanges 25 at the bottom, and the end pieces have corresponding parts 26 and 27, and these flanges 25 and 27 meet the corresponding flanges in the lower part of the case as shown in Figure 4. The meeting flanges of the upper and lower parts are covered by angles 28 as shown clearly in Figures 3 and 4, and bolts may be extended through the angles and through the adjacent flanges to make the joint exceedingly tight and strong. Furthermore it will be seen by reference to Figure 4 that the whole joint lies within the plane of the adjacent sides so as not to interfere with close packing.

25 The top portion of the extension 22-23 has the inclined parts 29 and flanges 30, the latter meeting the flanges 31 on the inclined part 32 of the cover 33, and the flanges 30 and 31 can be bolted or otherwise fastened together.

35 As in the other modification, it will be seen that if the extension 22-23 is not used, the cover 33 will fit on the lower part of the case, and as already stated with reference to the structure shown in Figure 2, the case can be provided with a plurality of such extensions if desired, without at all changing its characteristics.

I claim:

- 40 1. An extension packing case comprising a main member having inclined peripheral flanges lying within the plane of the adjacent sides of the case, an extension having inclined corners and peripheral flanges to fit the flanges of the main part of the case, and a cover having flanges to fit those of the extension and the main part of the case whereby the cover can be used either for the main case or for the extension.
- 45 2. An extension packing case comprising a main member having inclined parts and outwardly extending inclined flanges at the periphery, an extension having corresponding inclined parts and flanges, and an angle brace uniting the flanges of the main part and the extension.

3. An extension packing case comprising a main member having inclined parts near the periphery with outwardly extending flanges thereon, said flanges lying within the plane of the adjacent sides of said member, an extension having flanges corresponding to those of the main member and adapted to meet said flanges edge to edge, and an angle brace uniting the said flanges, said brace lying within the plane of the adjacent sides of the case.

4. An extension packing case comprising a main member having sides and end portions with inclined edge parts and outwardly extending flanges thereon, an extension having similar sides, ends, inclined parts and flanges, whereby the flanges of the extension and main member meet edge to edge, and a fastening brace to secure the flanges of said parts together.

5. An extension packing case comprising a main member having sides and ends with inclined edge portions and outwardly extending flanges, whereby the flanges are brought within the planes of adjacent sides of the said member, an extension similar to the main member and having similar inclined parts and flanges, the flanges of the extension being arranged to meet those of the main member, means for fastening the flanges together, and a top shaped to fit either the main member or the extension.

6. In an extensible packing case, a body having marginal inset portions at opposite sides thereof, and an extension having marginal inset portions coinciding with the marginal inset portions of the body for fitting contact therewith, said portions being correspondingly inclined relative to each other, and means joining said portions together.

7. In an extensible packing case, a body having marginal inset portions at opposite sides thereof, and an extension having marginal inset portions coinciding with the marginal inset portions of the body for fitting contact therewith, said portions being correspondingly inclined relative to each other, and means joining said portions together, and a cover fitting into the marginal portions of either the body or extension.

In testimony whereof, I have signed my name to this specification this 27th day of April, 1925.

110

ROBERT W. STANLEY.
